UNITED STATES PATENT OFFICE

91,974

DESIGN FOR A RADIATOR OR THE LIKE

Arthur L. Stevens, Evanston, Ill.

Application August 7, 1933, Serial No. 48,957

Term of patent 14 years

To all whom it may concern:

Be it known that I, ARTHUR L. STEVENS, a citizen of the United States, residing at Evanston, in the county of Cook and State of Illinois, have invented a new, original, and ornamental Design for a Radiator or the like, of which the following is a specification, reference being had to the accompanying drawing, forming part thereof.

The drawing is a perspective view of my novel design for a radiator or the like.

I claim:

The ornamental design for a radiator or the like, substantially as shown.

ARTHUR L. STEVENS.
